UNITED STATES PATENT OFFICE.

ALBERT ERICKSON, OF CHICAGO, ILLINOIS, ASSIGNOR TO SPLITDORF ELECTRICAL COMPANY, OF NEWARK, NEW JERSEY, A CORPORATION OF NEW JERSEY.

IGNITION DEVICE.

1,318,197.

Specification of Letters Patent.

Patented Oct. 7, 1919.

Application filed July 25, 1917. Serial No. 182,728.

To all whom it may concern:

Be it known that I, ALBERT ERICKSON, a citizen of the United States, residing at 948 Addison St., city of Chicago, in the 5 county of Cook and State of Illinois, have invented certain new and useful Improvements in Ignition Devices, of which the following is a specification, reference being had to the accompanying drawing.

10 This invention relates to an ignition device for internal combustion engines, and has for its object the provision of a make-and-break igniter in combination with a magneto generator combined with actuating 15 mechanism whereby the generator and igniter may be positively operated in unison, so as to provide a spark of maximum efficiency.

20 A further object of the device is the provision of an operating mechanism whereby the magneto and igniter are inter-connected in which all adjustments as heretofore employed have been eliminated, the actuating members being so formed and positioned 25 relative to each other that inaccuracies in timing due to wear will be negligible.

25 A further object is the provision in combination with the actuating mechanism of an engine driven push finger adjustably 30 mounted whereby the timing of the trip of the actuating mechanism and the advance and retard of the spark is easily accomplished.

Ancillary objects will more fully herein- 35 after appear.

In the accompanying drawings in which like figures of reference denote the same parts wherever they are shown,

Figure 1 is a front view of the device con- 40 stituting my invention with the magneto removed from its support and with the actuating mechanism in its normal or "at rest" position;

Fig. 2 is a view of the engine driven trip 45 finger with the early and late eccentric in the early or advanced position;

Fig. 3 is a view of the early and late eccentric in the late or retarded position;

Fig. 4 is a view of the mechanism shown 50 at Fig. 1, at the instant the same is about to be tripped;

Fig. 5 is a view of the mechanism after its release showing the movable electrode arm and trip finger in engagement, the trip finger 55 being omitted.

Fig. 6 is a side view of the complete device showing the magneto in place;

Fig. 7 is a view of the cylinder end of the igniter proper, the points being closed which is the position they occupy with the 60 parts in the position shown at Figs. 1 and 4;

Fig. 8 is a view of the cylinder end of the igniter with the points open, which occurs when the mechanism is in the position shown 65 at Fig. 5;

Fig. 9 is a view partly in section on line A—B, Fig. 1.

The numeral 1 denotes the flange of a framework supporting the various parts. 70 This is preferably a casting adapted to be attached to the engine cylinder and comprises the body 2 of the make-and-break igniter, the flange portion 1, and the supporting shelf or bracket 4, on which the 75 magneto is mounted. For the sake of brevity, I will hereafter designate this entire casting as the igniter bracket. That portion of the igniter bracket forming the igniter body 2, adapted to project into the 80 engine cylinder is drilled to receive the stem of the movable electrode 3, and the body 4 of the stationary electrode, it being understood that the stem 5 of the latter is suitably insulated from the body 4, and conse- 85 quently from the igniter body 2 and all other parts of the device, preferably by means of the mica insulation 6 and the insulating bushing 7.

Upon the inner or cylinder end of the 90 movable electrode 3 and the insulated stem 5 are the contact points 8 and 9 constituting the ordinary make-and-break igniter. It will be understood that all of this igniter mechanism may be of any suitable form for the 95 proper performance of the purpose for which it is employed.

On the outer end of the movable electrode 3 is secured the arm 10 attached to 3 in the position shown at Fig. 1, the igniter points 100 in the cylinder being normally closed as shown at Fig. 7, this being accomplished by means of the spring 11, which normally pushes arm 10 to the right, Fig. 1, thereby holding the points in engagement. The 105 fixed end of this spring engages the abutment 12 on the body of the igniter bracket.

A helical spring 11^a is positioned about the movable electrode 3 and tends normally to shove the same outwardly thereby hold- 110

ing the stem of 3 on its seat in the igniter body 2 and preventing leakage of the engine gases.

A pin 13 is suitably secured in the igniter bracket and on this pin is placed the trip lever 14, which has two outwardly extending pins 15 and 16 carrying the usual spring rollers as shown, which are engaged by the trip springs 17 and 18, the fixed ends of 10 which engage similar rollers as shown mounted on pins 19 and 20 suitably positioned in the igniter bracket.

The trip finger 21 is mounted upon a support 22 secured to an actuating rod 23 such as the exhaust valve rod of the engine. Between the support 22 and the trip finger is the early and late eccentric indicated at 24, this being eccentric to the center pin 25. When the finger 26 is thrown to the left, 20 Fig. 2, the distance from the center of the pin 25 to the point 27 is increased. When 26 is thrown to the right as shown at Fig. 3, the distance from the center of 25 to point 27 is decreased. The trip finger is pushed 25 upward by means of a spring 28, and is therefore held in engagement with the trip lever 14 as shown in the figures.

In Fig. 6, the magneto generator is shown connected to the operating mechanism just 20 described, and it will be observed that this is accomplished by means of the bifurcated magneto crank 29 engaging the pin 15 in the trip lever, it being understood that this magneto crank is securely attached to the 35 shaft 30 of the generator which may be of any suitable type wherein the oscillation of a member comprising any form of rotor or wire wound armature produces a suitable current.

40 In the embodiment of the invention herein disclosed, the magneto generator is designated by the numeral 31, and is detachable from the igniter bracket as a complete unit by merely removing the bolt or 45 bolts indicated at 32, and in this connection it will be observed that it is not necessary to disassemble the generator in order to remove the same, but that the complete operative generator is placed upon the support, 50 shelf or bracket 4 on which it is suitably and definitely positioned in relation to the other working parts of the device.

A suitable connection is made between the live terminal of the said generator and the 55 binding nuts on the stationary electrode stem 5, the circuit being completed through the contact points in the cylinder, through the body of the igniter bracket 1 and to the framework of the magneto.

60 The mechanism being connected up ready for operation and it being understood that rod 23 reciprocates thereby carrying the trip finger 21 back and forth underneath the trip lever 14, it will be presumed that 65 the device is in the normal position shown

at Fig. 1, and that the trip finger is moved to the left. 27 will engage 33 and the trip lever will be rotated clockwise on the pin 13 carrying with it springs 17 and 18. The trip lever will continue to rotate until it reaches the position shown at Fig. 4, whereupon the cam nose 34 of the trip lever 14 having continued to push downwardly upon the upper surface of the trip finger 21, forces 27 and 33 out of engagement with 75 each other, thereby releasing the lever 14, which suddenly rebounds, due to the action of the springs 17 and 18.

Now it will be observed from a study of Fig. 1 that normally the cam 35 on the 80 movable electrode arm 10 and the cam 36 on the trip lever 14 are out of engagement, that is to say a clear space exists between them, and therefore the igniter points in the engine cylinder are held closed as shown 85 in Fig. 7, by reason of spring 11, and this condition also exists during the cocking of the mechanism, and until the mechanism reaches the position shown at Fig. 5, where it will be observed that the cam face 36 90 has moved sufficiently to the left to engage the cam 35 striking the latter a sudden blow, compressing the spring 11 and causing a sudden opening of the contact points which assume the position shown at Fig. 8. At 95 the instant the points open it will be observed that the magneto crank 29 is moving, therefore the generator 31 is being actuated, and the rotor of the said generator is so positioned relative to the crank 29 that the 100 maximum current is available in unison with the opening of the points in the cylinder and thereby an efficient igniting spark is obtained.

The contour of the engaged surfaces of 105 the cams 35 and 36 is so shaped and proportioned and the relative radial diametrical dimension of the cams so proportioned in relation to the length of the arm on the movable electrode carrying the point 8, that the wear of points 8 and 9 do not appreciably affect the timing of the device, for although wear of the points may permit cam 35 to approach cam 36 slightly, the relative shape of the opposed faces of 35 115 and 36 is so determined that this slight coming together of the cams is not of consequence.

Devices in the prior art have always employed adjustable means in connection with 120 the movable electrode arm 10 whereby the timing of engagement of it by the trip lever 14 could be adjusted; and it will be observed by my improved arrangement that the necessity for such adjustable means has been 125 eliminated and therefore the trouble and annoyance caused by said adjustable means coming loose, the same usually comprising a screw with lock nuts, is avoided.

When the point 27 is disengaged from the 130

tooth 33 and the springs 17 and 18 cause the trip lever 14 to rotate anti-clockwise beginning at the position shown at Fig. 4, and passing through the middle stage as shown at Fig. 5, it will be observed that cam 36 is free to rotate past cam 35, and that the engaged surfaces of these cams are so presented to each other that the tendency of the trip 14 to stop in its radial anti-clockwise motion is reduced to a minimum. This enables the armature or rotor of the generator 31 to continue to rotate with the trip lever 14 as it is connected thereto, which is not the case when the mechanism strikes a direct opposition such as adjusting screws in the movable electrode arm as employed in the devices shown in the prior art. In other words my arrangement is now free acting on the return stroke, as during this return stroke the entire actuating mechanism does not meet with any direct opposition, the motion between the cams 35 and 36 being sliding in its nature.

It will also be observed that on the return stroke of the mechanism that the upturned portion 37 of the trip finger will engage the rear heel 38 of the trip lever, which prevents the trip finger from rising an undue distance due to the pressure of spring 28, and the slope of the end 37 also prevents noise during the operation of the device.

A further advantage in the construction of the trip finger shown is that in the event the mechanism is cocked by hand in the position shown at Fig. 4 and that the trip finger 21 may be in some other position than that shown at Fig. 4, nose 37 will prevent the engagement of the trip finger 21 and the trip lever 14. It will also be noted that the trip finger 21 is definitely displaced in relation to trip lever 14 by reason of the employment of the cam nose 34 when the finger 21 is in either the advance position shown at Fig. 2 or the retard position shown at Fig. 3. The drawings show the complete mechanism described, as projecting through the cylinder wall 39 of an internal combustion engine and the igniter bracket is secured thereto in any suitable manner as by the bolt and nut indicated at 40.

What I claim is:—

1. An ignition device comprising a fixed and a movable electrode, spring means for holding the electrodes closed, a trip lever, independent spring means associated with the trip lever, means for moving the trip lever against the action of its spring and for releasing the same, a non-adjustable member carried by and operating said movable electrode, a non-adjustable member carried by and movable with the trip lever for engaging the non-adjustable member carried by the movable electrode.

2. An ignition device comprising a fixed

and a movable electrode, spring means for holding the electrodes closed, a trip lever, independent spring means associated with the trip lever, means for moving the trip lever against the action of its spring and 70 for releasing the same, a cam shaped member carried by the movable electrode for operating the same, and a cam shaped member carried by said trip lever for engaging said cam shaped member carried by the movable 75 electrode.

3. An ignition device comprising a fixed and a movable electrode, a trip lever, spring means associated with the trip lever, means for moving the trip lever against the action 80 of the spring and for releasing the same, a cam shaped member carried by the movable electrode for operating the same, and a cam shaped member carried by said trip lever for engaging said cam shaped member carried by the movable electrode, said cam shaped members being so shaped and disposed relative to each other that said cam shaped member carried by the trip lever will have a sliding or shifting line contact engagement with the cam member carried by the movable electrode. 90

4. An ignition device comprising a fixed and a movable electrode, a trip lever, spring means associated with the trip lever, means for moving the trip lever against the action 95 of the spring and for releasing the same, a sleeve attached to the electrode, a cam formed integral with the sleeve, said trip lever having a projecting cam adapted to 100 engage the cam on said sleeve, for separating the electrodes, said cam shaped members being so shaped and disposed relative to each other that said cam shaped member carried by the trip lever will have a 105 sliding or shifting line contact engagement with the cam member carried by the movable electrode.

5. An ignition device comprising a fixed and a movable electrode, a trip lever, spring means associated with the trip lever, means for moving the trip lever against the action 110 of the spring and for releasing the same, a sleeve fixed to the movable electrode, a cam integral with said sleeve, a cam integral 115 with the lever and adapted to engage the cam on the sleeve, said cams being shaped so that they have a sliding or shifting line contact engagement with each other.

6. An ignition device comprising a fixed 120 and a movable electrode, a trip lever, spring means associated with the trip lever, means for moving the trip lever against the action of the spring and for releasing the same, a cam connected to and operating said movable electrode, a cam connected to said trip lever and adapted to engage the cam for operating the electrode, said cams being 125 shaped and positioned relative to each other, so that the cam on the trip lever will have 130

- 4
- a sliding and shifting engagement with the cam for operating the electrode and whereby the cam on the trip lever by a continued movement would slip by the cam for operating the electrode.
5. An ignition device comprising a fixed and a movable electrode, a trip lever, spring means associated with the trip lever, means for moving the trip lever against the action of the spring and for releasing the same, a member connected to the movable electrode for operating the same, and means carried by the trip lever for engaging said member for moving the same to separate the electrodes, the point of engagement between said means and said member being a shorter distance from the pivotal axis of the movable electrode than the contact point carried by the movable electrode.
10. An ignition device comprising a fixed electrode, a movable electrode including a supporting stem, an arm carried thereby, a contact point mounted on said arm, a trip lever, spring means associated with the trip lever for operating the same, means for moving the trip lever against the action of the spring and for releasing the same, a member attached to said stem of the movable electrode, means carried by the trip lever for engaging said member for operating the movable electrode, the point of engagement between said means and said member being a shorter distance from the axis of the stem of the electrode than the contact point carried by the arm of the movable electrode.
15. An ignition device comprising a supporting bracket, a fixed electrode carried by said bracket, a movable electrode mounted in said bracket, said movable electrode having an operating member fixed thereto, an abutment carried by the bracket, a compression spring interposed between the abutment and said member for normally holding the contacts closed, and a spring actuated tripping mechanism mounted independently of the movable electrode for engaging said member for separating the contacts.
20. An ignition device comprising a supporting bracket, a fixed electrode carried thereby, a movable electrode mounted in said bracket, a sleeve carried by said movable electrode, a projecting member formed integral with said sleeve, and having one side thereof substantially flat and the other side thereof cam shaped, an abutment on the bracket, a compression spring between the flat face of said member and said abutment, and spring actuating tripping mechanism mounted independently of the movable electrode having a contact cam for engaging the cam face of the member on the movable electrode for separating the contacts of the electrodes.
25. An igniter device comprising a fixed and a movable electrode, a trip lever supported independently of the movable electrode, spring means associated with said trip lever for actuating the same, a trip finger for actuating the trip lever, said trip lever having a tooth adapted to be engaged with the trip finger, and a projecting cam for actuating the movable electrode.
30. An igniter device comprising a fixed and a movable electrode, a trip lever, spring means associated with said trip lever for actuating the same, a trip finger for actuating the trip lever, said trip lever having a tooth adapted to be engaged by the trip finger, a projecting nose for releasing the trip finger from the tooth, and an actuating cam for operating the movable electrode.
35. An igniter device comprising a fixed and a movable electrode, a trip lever, spring means associated with the trip lever for actuating the same, an operating trip finger for turning the trip lever against the action of said spring means, said trip lever having a tooth adapted to be engaged by said trip finger, means for yieldingly pressing the trip finger toward the trip lever, said trip finger having an upturned end adapted to engage the trip lever at a point in rear of the tooth.
40. An igniter device comprising a fixed and a movable electrode, a trip lever for actuating the movable electrode, spring means associated with the trip lever, a trip finger for actuating and releasing the trip lever, a reciprocating rod and an eccentric bushing connection between the rod and the trip finger, which may be shifted for varying the position of the trip finger for timing purposes.
45. An igniter device comprising a fixed and a movable electrode, a trip lever for actuating the movable electrode, spring means associated with the trip lever, said trip lever having a tooth, a trip finger having a shoulder adapted to engage said tooth, means for yieldingly pressing said trip finger toward the trip lever, means for releasing the trip finger from the trip lever, a reciprocating rod, an eccentric bushing connection between the reciprocating rod and the trip finger, said connection being shiftable for varying the timing of the trip finger.
50. An igniter device comprising a fixed and a movable electrode, a trip lever for actuating said electrode, spring means associated with said trip lever, the reciprocating trip finger for actuating and releasing the trip lever, a reciprocating rod, a pin carried by said rod, an eccentric bushing on said pin, said trip finger having a collar engaging said bushing, yielding means for holding said bushing in adjusted position, and means whereby said bushing may be shifted.
55. An ignition device comprising an igniter bracket having therein fixed and

- movable electrodes, a cam on the movable electrode, a spring adapted to engage said cam to yieldingly hold said electrode in a predetermined position, an abutment for 5 said spring projecting from the face of said bracket, a shaft in said bracket, a trip lever supported by said shaft, said lever comprising a cam surface adapted to engage said first mentioned cam, a tooth on said lever, 10 a cam nose about said tooth, and spring means between said trip lever and said bracket whereby the trip lever is yieldingly held in a predetermined position, substantially as described.
- 15 18. An ignition device comprising a bracket having fixed and movable electrodes therein, a cam on the movable electrode, a spring adapted to engage said cam and thereby yieldingly hold the electrode in a predetermined position, an abutment on the 20 bracket for positioning said spring, a pair of arms extending from the body of said bracket and forming spring anchorages, a shaft positioned below said cam, a trip lever 25 on said shaft having a cam portion adapted to engage said first cam and another portion having an engaging tooth, a spring for the trip lever whereby it is held in a predeter-
- mined position, and actuating means adapted to engage said tooth for operating the trip lever, substantially as described.
19. An ignition device comprising an igniter bracket having a body portion containing a pair of igniter electrodes, a cam on one of said electrodes, a spring pressing 35 said cam and thereby holding said electrode in a predetermined position, a trip lever mounted on said bracket and having its rotative center below said cam, said trip lever having a cam surface adapted to engage said first mentioned cam, springs connected to 40 said trip lever whereby it may be held in a predetermined position, a laterally extending shelf, a magneto generator detachably secured to said shelf and a connection between 45 said generator and trip lever whereby the generator may be removed from the bracket without removing the trip lever therefrom, substantially as described.

In testimony whereof I hereunto affix my 50 signature in the presence of two witnesses.

ALBERT ERICKSON.
